BOTTLE

Ottavio Riccadonna, Canelli, Asti, Italy, assignor to Ottavio Riccadonna S.p.A., Canelli, Asti, Italy

Filed July 26, 1966, Ser. No. 3,218

Term of patent 7 years

U.S. Cl. D9—77

Int. Cl. D9—01

I claim:

The ornamental design for a bottle, as shown.
